The ornamental design for a shower organizer, as shown and described.

DESCRIPTION

FIG. 1 is a front elevational view of our shower organizer;
FIG. 2 is a rear elevational view of our shower organizer;
FIG. 3 is a top plan view of our shower organizer;
FIG. 4 is a bottom plan view of our shower organizer;
FIG. 5 is a right side elevational view of our shower organizer; and,

FIG. 6 is a left side elevational view of our shower organizer. The partial showing of the mesh in FIG. 1 is for ease of illustration. It is understood that the mesh covers the entire area where only a portion is shown.
